UNITED STATES PATENT OFFICE.

JOHN F. ROTE, OF READING, PENNSYLVANIA.

VEGETABLE-CUTTER.

SPECIFICATION forming part of Letters Patent No. 588,606, dated August 24, 1897.

Application filed June 13, 1896. Serial No. 595,379. (No model.)

To all whom it may concern:

Be it known that I, JOHN F. ROTE, a citizen of the United States, residing at Reading, county of Berks, State of Pennsylvania, have 5 invented certain Improvements in Vegetable-Cutters, of which the following is a specification.

My invention relates to an improved combination vegetable-cutter which is adapted 10 to perform either of the several operations of cutting or slicing, shredding or stripping, or grating, with facility and in a perfectly-satisfactory manner.

The invention is fully described in connection 15 with the accompanying drawings, and the novel features are specifically pointed out in the claims.

Figure 1 is a front elevation of the machine, partly in section, so as to show more clearly 20 the several features of the construction. Fig. 2 is a plan view showing the cover removed and the cutter-wheel in cross-section through the openings for the knife and the toothed cutter-bar. Fig. 3 shows two views of the 25 toothed cutter-bar. Fig. 4 shows three views of the cap for said bar and the pivoted locking-arm. Fig. 5 shows the knife-arm detached. Fig. 6 shows the flanged center piece with a portion of the grater-disk attached.

30 A A' represent the supporting-casing of my improved machine, preferably formed in two parts, as shown, and bolted together by means of lugs a a'. This casing is provided with bearings a³ a³ for a horizontal shaft K, 35 to which is secured the cutter disk or wheel B. This wheel is dished to form a bulging or convex working face, and has a rearwardly-tapering hub B', filling the space between the bearings a³ a³. Upon this tapering hub 40 is adjustably secured a knife-arm F, the base f of which slides forward or backward upon the hub and is fastened at any desired point by means of a set-screw F', which engages a slot f² in the base, while the knife-attaching 45 portion f' passes freely through an opening b' in the web of the wheel in a direction practically at right angles to the inclined face of the wheel, thus allowing the cutting edge of the knife F² to be set a greater or less distance 50 from the outer working face of the wheel to regulate the thickness of the cut. In order to adapt this wheel to do a variety of work

by means of very simple changes, I provide for both shredding and grating attachments to the cutter-wheel F, said grater, shredder, 55 and wheel being relatively of peculiar construction, whereby the necessity of removing either of the cutting devices from the wheel while the device is being used as a grater is avoided. The former attachment consists of 60 a toothed bar G, which fits reversibly in an opening b² in the wheel, and has flanges g, which lap over the edges of the opening. This bar has a series of cutting-teeth g' projecting from one face, which face is set outward when 65 the machine is intended to operate as a shredder. At other times the bar is inserted in the opening b² reversely—that is, with the teeth at the rear—and in either case it is firmly held in the opening by means of a locking 70 mechanism which consists, as shown, of a cap-piece H and a swinging arm I, which is oppositely notched at its opposite ends, so as to engage or disengage headed screws i i, projecting rearwardly from the wheel through 75 perforated bosses h h of the cap-piece. The lower edge h' of the cap-piece bears upon the flanges g g of the toothed bar G, thus securely holding the latter when the notched arm I is turned under the heads of the screws, and a 80 slight movement of the latter serves to tighten or loosen the cap-piece.

The grater-disk J is dished similarly to the wheel B, but to a somewhat greater extent, and is secured to the outer face of the latter 85 by means of a flanged center piece J', which is strung upon the shaft K and serves to press the grater-disk against the face of the cutter-wheel by means of a nut j², the outer edge of the grater-disk being thus forced outward against a circular offset b near the periphery of the cutter-wheel, thereby securing proper rigidity of the grater, which may also be positively prevented from turning, if desired, by providing a projection on the rear 90 of the disk to engage a recess or opening in the cutter-wheel.

The nut J² preferably enters a recess in the center piece J', which latter enters a central recess in the face of the wheel in order to reduce the projection of the nut beyond the face of the wheel.

The supporting-casing A A' is fastened to a shelf or table, as usual, by means of a suit-

able bracket A², and the front portion A is provided with a feeding-table D, arranged to slide in and out upon a fixed bracket C, having a slot c, in which the clamping-screw d moves. The inner edge c' of the feed-table is adapted to serve as a lower shearing-blade, and is adjusted so as to just clear the rotating knife F², whether the latter be adjusted for a thin or thick cut, thus insuring the cleanest possible cutting action. This portion of the casing is also recessed interiorly, as indicated at a⁴, so as to permit the projecting portion of the thumb-nut J², which fastens the grater-disk, to be handled with the greatest convenience in placing or removing the disk.

The rear portion A' of the supporting-casing is provided with bosses a⁵ and a⁶, upon which to mount suitable gear-wheels, (not shown,) through which to give a rapid rotary motion 20 to the cutter-wheel B. In connection with the front portion A it forms a chute-like extension for conveying the cut material to a bottom outlet a⁷, through which it is delivered into a suitable receptacle. The casing 25 is completed by a cover E, which is hinged at a' to the supporting-casing A A' and conveniently fastened to the outer end e' by suitable means consisting in the construction shown of a swinging bolt e² with thumb-nut, 30 which is pivoted between lugs a² on the supporting-casing and swings into or out of engagement with jaws e' on the cover. An opening e⁴ in the front of the cover, guarded by a projecting flange e³, allows the material 35 operated upon to be held in contact with the working face of the cutter-wheel while resting upon the feed-table D.

By my improved construction I have provided a neat, compact, and comparatively inexpensive machine which is adapted to do a great variety of work in a rapid, satisfactory, and cleanly manner. The knife-arm is readily adjusted upon the tapering hub of the cutter-wheel, the knife moving substantially 40 at right angles to the inclined wheel-face, as stated, and when properly set it cannot be moved outward from its position by the force of the cut, which tends to pull it forward and thereby increase the depth of the cut. The 45 toothed cutter or shredding bar is always in place, with the cap ordinarily covering the teeth, and needs only to be reversed to throw it into operation, which is very easily done.

The dished grater-disk provides a rigid operating-surface when attached to the cutter-wheel as described, does not require the removal of the knife or shredding-bar, and is itself easily applied or removed.

The construction as specifically described 60 and shown may obviously be considerably modified without departing from the spirit of my invention.

What I claim is—

1. In a vegetable-cutter the combination 65 with a supporting-casing of a rotary cutter-wheel having a convex or conical working face, a tapering hub, and a knife-opening,

and a knife-arm guided upon and adjustably secured to the tapering surface of said hub to regulate the projection of the knife through 70 said opening, substantially as set forth.

2. In a vegetable-cutter the combination with a supporting-casing of a rotary wheel mounted therein and formed convex on the outer face, with a circular offset at the periphery and a separately-formed dished grater-disk removably secured to said outer face by means of a flanged center piece and a nut engaging a screw-thread on the wheel-shaft, the outer edge of said grater-disk seating against 80 said circular offset, substantially as set forth.

3. In a vegetable-cutter the combination with a supporting-casing of a rotary cutter-wheel having a radial opening b², a cutter-bar reversibly fitting said opening and having a series of cutter-teeth projecting from one face thereof and the opposite face plain, and means for reversibly securing said cutter-bar in said opening, all substantially as set forth.

4. In a vegetable-cutter the combination with a supporting-casing of a rotary cutter-wheel having a radial opening b², a cutter-bar reversibly fitting said opening and having a series of cutter-teeth projecting from one face thereof, a rear cap for said cutter-bar and means as described for removably securing the bar and cap to the wheel substantially as set forth.

5. In a vegetable-cutter the combination with a supporting-casing of a rotary cutter-wheel having a rearwardly-extending hub and a knife-opening, and a knife-arm guided upon and adjustably secured to said hub to regulate the projection of the knife through said opening, the knife-attaching portion of said arm passing freely through said opening in a direction approximately at right angles to the face of the wheel, substantially as set forth.

6. In a vegetable-cutter the combination with a supporting-casing, of a rotary cutter-wheel mounted therein and having a convex or conical working face, and a separately-formed grater-disk of sheet metal dished or concaved to a slightly greater extent than 115 said outer face, and clamping mechanism for firmly seating said grater-disk against said face substantially as set forth.

7. In a vegetable-cutter the combination with a rotary cutter-wheel having a convex 120 working face and a central recess, and with a centrally-perforated sheet-metal grater-disk fitting against said face, of a flanged center piece and a nut engaging the wheel-shaft to fasten said disk, said nut entering a recess in 125 the center piece, and the latter entering the central recess of the wheel substantially as set forth.

8. The combination of the rotatable wheel, having cutting means permanently attached thereto, and provided with an offset around its periphery, and fastening means strung upon the shaft of said wheel, said fastening means and offset being designed to coöperate

in securing a dished grater removably and rigidly in place over said cutting means, substantially as described.

9. The combination of the dished cutting wheel, having an offset around its periphery, a sleeve having a recess in its end, a flanged center piece strung upon the shaft of said wheel and entering said recess, and a binding-nut for said center piece, the whole being designed to coöperate in securing a dished grater-disk removably in place upon said wheel.

10. The combination with a wheel having an offset around its periphery and provided with cutting devices, of a dished grater-disk having its periphery engaged with said offset, and means for clamping said disk over said cutting devices and so that it will rotate with said wheel.

11. The combination with the cutting-wheel, having an offset around its periphery, of a sleeve, having a recess in its end, a flanged center piece strung upon the shaft of said wheel and entering said recess, a binding-nut for said center piece, and a dished grater removably held in place by said offset, center piece, &c.

12. A vegetable cutter, shredder and grater, embodying a wheel formed with radial openings, an adjustable cutter projecting through one of said openings, a cutter-bar reversibly fitting in the other opening and having a se-

ries of cutting-teeth projecting only from one face thereof, and a removable grater, having a flanged center piece and a nut for attaching it to the wheel over said cutter.

13. A vegetable cutter, shredder and grater, embodying a dished wheel, formed with radial openings and with a circular offset at its periphery, an adjustable cutter projecting through one of said openings, a cutter-bar reversibly fitting in the other opening and having a series of cutting-teeth projecting only from one face thereof, and a separately-formed dished grater-disk, removably secured to said outer face, by means of a flanged center and a nut, the outer edge of said grater-disk seating against the circular offset, as specified.

14. The combination with the dished wheel, having an offset around its periphery, of a cutter-bar, reversibly fitted to said wheel and having teeth projecting from one of its faces only, a removable grater-disk mounted upon the shaft of said wheel and having its edge seated against said offset, and means for clamping the center of said disk against the wheel, as specified.

In testimony whereof I affix my signature in presence of two witnesses.
